said pivotal axis than the bottom of said indentation, means for holding the temple in open position comprising a resilient plate carried by said lug and extending arcuately rearwardly providing a catch engaging portion entering said indentation and engaging said catch and holding the temple in open position and slideable along said cam-shaped surface and being flexed outwardly by such sliding upon swinging said temple on its pivotal axis.

2. In an ophthalmic mounting as in claim 1 wherein said indentation provides a shoulder to be engaged by said catch engaging portion to limit the outward swinging movement of said temple.

JOHN N. NELSON.
